[57] CLAIM

The ornamental design for a phototherapy cabinet, substantially as shown.

DESCRIPTION

FIG. 1 is a front elevational view of a phototherapy cabinet embodying our new design in a closed position. FIG. 2 is a top plan view of the phototherapy cabinet shown in FIG. 1.

FIG. 3 is a rear elevational view of the phototherapy cabinet of FIG. 1.

FIG. 4 is a bottom plan view of the phototherapy cabinet of FIG. 1.

FIG. 5 is an interior elevational view of the phototherapy cabinet of FIG. 1 in an open position.

FIG. 6 is a cross-section taken on line 6—6 of FIG. 5.

FIG. 2

FIG. 3

FIG. 1

FIG. 4

FIG. 6
